Their Attorney

UNITED STATES PATENT OFFICE.

DWIGHT R. NORRIS, WALTER H. BAKER, AND EDWARD C. WALKER, OF ST. LOUIS, MISSOURI, ASSIGNORS TO NATIONAL LEAD COMPANY, OF ST. LOUIS, MISSOURI, A CORPORATION OF NEW JERSEY.

METAL SHIPPING PACKAGE.

Application filed August 1, 1921. Serial No. 488,971.

To all whom it may concern:

Be it known that we, DWIGHT R. NORRIS, WALTER H. BAKER, and EDWARD C. WALKER, all citizens of the United States, and residing at St. Louis, in the State of Missouri, have invented a certain new and useful Improvement in Metal Shipping Packages, of which the following is a specification.

This invention relates to shipping packages and more particularly to that type of package which may be used repeatedly and which is arranged for locking during shipment.

The package of the present invention is designed especially for shipping such articles as bars of solder which are heavy and, therefore, require a substantial package and being more or less valuable, are often subject to theft which is to be guarded against in locking the package.

One of the objects of this invention, therefore, is to provide a shipping package which shall be strong so as to withstand the hard usage usually suffered in the shipment of heavy articles, and which shall be cheap and simple to manufacture.

Another object of this invention is to provide a shipping package with a cover which shall be easily removable so as to remove the contents and which may be locked and sealed in place for shipment.

Further objects will appear from the detailed description taken in connection with the accompanying drawing, in which:

Figure 1 is a plan view of a shipping package embodying this invention; and

Figure 2 is a section on line 2—2, Figure 1.

Referring to the accompanying drawing, 40 1 designates the body of the can which is usually constructed of stout sheet metal. The package is cylindrical in form usually being made by the welded-can method and is provided with a bottom 2 having a flange, which together with the lower edge of the body 1 is rolled inwardly to provide a lower rim 3 which will reenforce the body and the bottom of the can.

The upper end of the can has a similar 50 inwardly rolled rim 4 which may, if desired, be rolled over a wire in a well known manner. This provides a reenforced rim which makes the can stiff and rigid.

A cover 5 is provided with a flanged rim

6 adapted to lap over the rim 4 of the can 55 and having a depressed central portion extending slightly into the can and within which the locking device is disposed. Underneath one edge of the top 5 a locking plate 7 is secured by means of rivets 8 or 60 other suitable means. This plate is provided with a lateral extension 9 adapted to take under the rim 4 as shown in Figure 2 so as to prevent the top from being lifted off of said rim.

Opposite to the locking plate 7, a bolt 10 in the form of a flat plate is slidably mounted upon the cover 5 by means of rivets 11 and elongated slots 12. This provides for the retraction of the bolt 10 so as to 70 disengage the rim 4 for removing the cover. The bolt is further provided with an eye 13 adapted to align with a pair of corresponding eyes 14 on the upper side of the cover 5. A slot 15 is provided in the cover 75 through which the eye 13 will project and along which it may move as the bolt moves. The bolt may thus be slid forward into locking position, as shown in Figure 2, so that the edge 16 thereof will take under the 80 rim 4 to secure the cover in place on the can. In this position the eyes 13 and 14 will be in alignment and may receive any suitable sealing means, such as the wire 17 and the lead-seal 18.

A shipping package is thus provided of rugged construction on account of the reinforcing rims 3 and 4. The upper rim 4, being rolled inwardly, also serves to engage the locking means 9 and 16 to secure the 90 cover 5 in place. The contents may be removed by breaking the seal 17, 18 sliding the bolt back and removing the cover by tipping it about the right hand side, Figure 2, of the rim 4 as a hinge, after which it 95 may be removed entirely from the can.

It is obvious that various changes may be made in details of construction without departing from the spirit of this invention; it is, therefore, to be understood that this 100 invention is not to be limited to the specific details shown and described.

Having thus described the invention, what is claimed is:

1. A shipping package having an inwardly extending rim, a removable cover having an upstanding marginal flange adapted to lap over said rim and provide a depressed

top, a retainer attached at spaced points to said top and adapted to take under said rim, a locking element movably attached at spaced points to said top, and means disposed within the depression of said top for sealing said locking element.

2. A shipping package having a rim, a removable cover on said rim, a locking piece on said cover adapted to engage said rim, a bolt slidably mounted underneath said cover and engaging said rim, an eye on said bolt, and a corresponding eye in said cover, said eyes being adapted to receive sealing means.

3. A shipping package having a rim, a cover on said rim, a locking piece on said cover, and engaging said rim, an oppositely disposed bolt slidably mounted underneath said cover and engaging said rim, an eye on said bolt, and a corresponding eye on said cover, said eyes being adapted to receive sealing means.

In testimony whereof we affix our signatures this 15th day of July, 1921.

DWIGHT R. NORRIS.
WALTER H. BAKER.
EDWARD C. WALKER.
